UNITED STATES PATENT OFFICE.

MAX TAIGMAN, OF NEW YORK, N. Y.

STARTING-BOX.

1,144,876.

Specification of Letters Patent. Patented June 29, 1915.

Application filed April 9, 1914. Serial No. 830,675.

To all whom it may concern:

Be it known that I, MAX TAIGMAN, a citizen of the United States, and a resident of the city of New York, borough of Manhattan, in the county and State of New York, have invented a new and Improved Starting-Box, of which the following is a full, clear, and exact description.

Among the principal objects which the present invention has in view are: to provide an apparatus of the character mentioned with a series of interchangeable unit devices to obviate the need for structural alteration in the apparatus when replacing a member thereof; to provide a relatively cheap circuit-breaking element to avoid arcing between the starting arm and resistance terminals of the box; to provide a simplified construction for the starting arm employed in the present box; to complete the circuit controlled by the box by placing the elements of the box in service position; and to provide simple and accessible adjustments for the moving operative members of the apparatus above mentioned.

Drawings.—Figure 1 is an end elevation of a box constructed and arranged in accordance with the present invention, showing in conjunction therewith a motor brake lever, a manipulating connection for said box, and a brake wheel or pulley to be operated on by said brake lever; Fig. 2 is a front elevation of the same, the brake wheel being omitted; Fig. 3 is a side elevation of a box constructed and arranged in accordance with the present invention, the cover of said box being removed; Fig. 4 is a rear view of the same, the back of the box being removed; Fig. 5 is a horizontal cross section taken as on the line 5—5 in Fig. 3; Fig. 6 is a horizontal section taken as on the line 6—6 in Fig. 3; Fig. 7 is a vertical cross section taken on the line 7—7 in Fig. 3; Fig. 8 is a detail view in perspective of the unit resistance spool and terminal block connected therewith; Fig. 9 is a detail view in perspective of the terminal block; Fig. 10 is a detail view in perspective, showing on an enlarged scale one of the terminal buttons; Fig. 11 is a detail view in perspective, showing a switch for controlling the current in conformity with the operation of the box,

and a jumper or circuit-connector normally attached to the box cover; Fig. 12 is a detail view in perspective, showing a cover for the box having the jumper bar disclosed in the previous figure, attached thereto; Fig. 13 is a detail view, in section, of a fragment of the starting lever with which the box is provided, showing in conjunction therewith a cross section of the switch rocker bar; Fig. 14 is a lay-out of the wiring employed in the starting box, showing in conjunction therewith the jumper bar or circuit-connector normally attached to the cover; Fig. 15 is a front elevation of a box constructed and arranged in accordance with a modified form of the invention, the resistance spool, terminal block and parts connected therewith, and the cover of said box being omitted; Fig. 16 is a rear elevation of the same, showing the cover in position, the back of the box being omitted; Fig. 17 is a vertical cross section taken on the line 17—17 in Fig. 16; Fig. 18 is a detail view in perspective of the box employed in the modified form shown in Figs. 15 to 17 inclusive.

Description.—The starting box and attachments shown in the drawings as connected therewith, are preferably employed in conjunction with electric motors having driving attachments and brake pulleys such as indicated by the numeral 25 in Fig. 1 of the drawings. A suitable brake shoe 26 is provided at the end of a brake beam or lever 27, which lever is pivoted on a bolt 28, and is provided with a reduced end 29 which extends through an eyelet 30 in the exposed end of a switch arm 31 of the improved starting box herein described. The pivot bolt 28 is fixedly mounted in the end of a rocking supporting arm 32. The arm 32 is pivoted on a bolt 33 extending from the frame of the starting box, and is adjusted as to working position by a screw bolt 34 operatively mounted in a bracket extension 35. The arm 31 and the lever 27 are coincidentally manipulated by a transmission connector 36, which is conveniently attached to a foot treadle or other manually manipulated device and engages the arm 31 by means of an eyelet 38 formed therein. Said arm, lever, and parts connected therewith are normally held in the out-of-service posi-

tion by a spring 37, which is directly connected with the arm 31.

The box above referred to has a continuous skeleton side frame 39. The frame 39 has a removable cover 40 and a removable back 41. When the cover and back above mentioned are removed, the device held in the skeleton frame may be engaged or handled from both sides. To support a resistance unit with which the box is supplied, the frame 39 is provided with inwardly-extending brackets 42, having tapped perforations to receive screw bolts 43. When the box is constructed in accordance with the preferred form of the invention, brackets 44 and 45 are employed, to which said stationary member of said switch is rigidly secured by screw bolts 46. In service, the box is suspended by legs 47, the preferred installation for the box being that wherein said box is suspended from the under side of a work-bench or shelf.

The resistance unit, as shown best in Fig. 8, comprises a spool 48, which is preferably constructed of a hollow, porcelain tube wrapped with suitable resistance wire, in electrical contact with which are mounted the metal bands 49, seen in said figure of the drawings. The bands are drawn tightly on the coil by screws 50, which screws pass between ear tabs on the ends of the bands, grasping between said ends the terminals of jumper straps 51. Before the straps 51 are installed, the spool 48 is capped by placing over each end thereof the cap portions 52 of side frames 53. The cap portions 52 are each provided with an externally-opening well 54, said wells being deep enough to contain nuts 55, which are fitted to the screw-threaded ends of clamping bolts 56. The frames 53 are provided with inwardly-projecting guide lugs 57 and 58. The lugs 58 are each provided with an inwardly edge-opening slot 59 sufficiently wide to permit the passage therethrough of the bolts 43. Said lugs 57 and 58 serve as guides to hold an insulating panel 60, which is provided with elongated perforations 61, also sufficiently wide to receive the bolts 43. The perforations 61 and the slots 59 are alined, and are elongated in the manner shown in the drawings and as above described, to permit an adjustment of the side frames 53 to the panel 60 and the spool 48, when assembling the unit. The panel 60 is preferably made of porcelain, and the perforations 61 and holes 62 formed therein are molded or cast in the panel, to avoid subsequent boring or machining of the panel. Through the holes 62 are extended the ends of small screw bolts 63, which are held rigidly in position by nuts 64. Under the nuts 64 are disposed washers, which subsequently form seats whereon rest the lower edges of terminal buttons 66. Under

the heads of the bolts 63, at the back of the panel 60, are washers 67, under which are extended the ends of the jumper straps 51, as shown best in Fig. 4 of the drawings. The buttons 66, as seen best in Fig. 3 of the drawings, are arranged in a path concentric with a pivot post 68 provided for the arm 31. When assembling this unit, the opportunity is afforded for laying or adjusting neatly and securely said straps. No other connection being necessary to the completion of a unit, the unit may be placed on the shelf of a store or warehouse in its fully-operative, and, if necessary, tested condition. When installed in service, the connector 69 is electrically connected to the button most suited to the conditions of service, the preferred form of connections being to extend the terminal end of said connector under a washer 67. The connector 69 is suitably mounted on the binding post 70 with which the box is furnished.

From the foregoing, it will be seen that the necessary electrical connections or alterations thereof may be conveniently and expeditiously effected in the manner indicated, by removing the back 41 of the box, which exposes the back of the panel 60 and screws 63 thereof which hold the connector 69 and the jumper straps 51, as seen best in Fig. 4 of the drawings.

The binding post 70 is electrically connected with one leg of an electric circuit, and with the buttons 66 through more or less of the resistance coil on the spool 48. The other binding post, 71, is electrically connected with the opposite leg of the electric circuit and with a pencil brush 72, which normally rests upon one or other of said buttons to slide thereover. The pencil brush 72 is slidably mounted in a head 73, best seen in Fig. 5 of the drawings, which head is at the end of the extension 74 on the arm 31. The extension 74 is supported by, but electrically insulated from, the arm 31 by an insulator pad 75. Said extension and arm are structurally connected by screws 76, which are likewise insulated from the arm 31.

It is the object of the present invention to prevent any leakage of current through the arm 31, which is accessible to, and liable to be touched by persons operating the starting box. To this end, the current delivered to the pencil brush 72 is transmitted through springs 77, said springs resting upon the pencil 72 and a plunger 78, which plunger is slidably mounted in a cylindrical collar 79 mounted on the extension 74 at one end thereof. Current is delivered to the plunger 78 from the bar 80 when the head 81 is engaged by the head 82 of a rocker 83. The rocker 83 is supported on a knife-edge 85, the frame having which, is structurally connected with, but insulated from the bar 80.

by means of a pad 84. At each side of the knife-edge 85 are guide uprights 86. The rocker 83 is provided at opposite sides with recesses 87, provided to infold said uprights, and thereby locate the operating position of said rocker. The plunger 78 is pressed upon the rocker 83 by one of the springs 77. To prevent any drag of the plunger 78 on the rocker 83, there is provided a roller 88, to facilitate the operation of which the rocker 83 is furnished with a relatively short runway or path 89, as best shown in Fig. 11 of the drawings. At one end of the bar 80 is provided a spring clip 90, between the jaws of which one end of a jumper-bar 91 extends. The opposite end of said jumper-bar enters the jaws of a clip 92, which clip is fashioned at the end of a rectangular frame 93, said frame being rigidly secured upon, but insulated from the frame 39 of the box. The frame 93 is electrically connected with the binding post 71, and thus forms what may be termed the one terminal of the electric circuit entering the starting box.

The jumper-bar 91 is mounted on the front cover 40 of the starting box. The jumper-bar is constructed from any suitable material, and is secured by means of screws 94 to the legs 95 of a plate 96. The plate 96 is furnished with edge opening slots 97, which, in the assemblage of the elements, engage screws 98, by which the plate is rigidly secured to the cover 40. The plate 96 and parts connected therewith are insulated from the cover 40 by a pad 99, as best seen in Fig. 12 of the drawings. The cover 40 is held in service position by a dowel hook pin 100, and by a spring latch 101. When the latch 101 snaps into holding position, the ends of the bar 91 have been forced between the jaws of the clips 90 and 92, and the working electric circuit for the control of which the box is designed, is completed or delivered on one side to the head 82 of the rocker 83, and on the other side to the buttons 66.

In the normal or inactive condition of the apparatus, the switch-arm 31 and extension 74 are moved by a spring 37 to a position where the pencil brush 72 rests on a dead button 102. The button 103 may be denominated as an auxiliary button, being dead under certain conditions; forming the first of the series of live buttons under other conditions; while under other conditions it is employed as a live shunt button, when the box is employed as a starter for a shunt-wound motor. This is most conveniently arranged in accordance with the present invention by connecting the button 103 by means of a jumper 104, with the adjacent live button 66. This winding and connection are conventional, and it is not considered necessary to further describe

them in this connection. To adjust the throw of the arm 31 with reference to the buttons 66, 102 and 103, I provide set screws 105, which engage tapped holes in the frame 39 of the box. The ends of said screws rest against spring plates 106, the ends whereof are loose and are covered by a leather pad 107. The pad 107 is employed primarily to deaden the sound which would be produced by the shoulders 108 striking the plate and pad when moved quickly to the out-of-service position, by the spring 37, or as quickly moved by the operator when depressing the end of the arm 31 attached to the connector 36.

When employing the modified construction shown in Figs. 15 to 18 inclusive, the switch having the rocker 83, the bar 80, the plunger 78, and parts connected therewith, is replaced by the elongated saddle spring 109, one end whereof is held rigidly under the foot of the terminal 110. Interposed between the frame of the box and the spring 109 is an insulating pad 111. To operatively engage the spring 109, the arm 31 is provided with a plate 112, at the end of which is extended a finger 113. Said finger has a path of movement concentric with the pivot post 68, to accommodate which is the office of the spring 109.

A spring bracket terminal 114 is disposed in corresponding relation to the terminal 110, and at the opposite side of the box the terminal 114 is electrically connected with the binding post 71. The two terminals are connected in service by a spring metal jumper 115, which, as shown best in Figs. 17 and 18 of the drawings, is rigidly mounted on the cover 40 by a single screw 116. The jumper 115 is insulated from the cover 40 by a pad 117. Said pad is turned at the sides, to be interposed between the jumper 115 and the spotting ridges 118 with which said cover is provided.

In the modified construction of the switch arm 31, as shown in Figs. 15 to 17 inclusive, the plate 112 is electrically connected to the extension 74 by screws 119. Both said extension and said plate are insulated from the arm 31 by the insulating pads 75 and 120. Also it will be noted in the modified construction, one only of the springs 77 is employed—that which depresses the pencil brush 72. An important factor in the present invention is, as pointed out, the facility for assemblage afforded by the unit construction of the combined elements constituting the box. When the box and units are constructed as described the assembling is accomplished as follows: The resistance unit 125 is placed within the frame 39, and the screw bolts 43 are passed through the slots 59 and perforations 61 and screwed upon the brackets 42, said bolts extending through said brackets to pass through the back 41 130

of the box, to be engaged by screw nuts provided to hold said back in position. If the resistance unit is equipped with the connector 69, the loose end of said connector is engaged with the binding post 70. This operation completes the assemblage as far as the resistance units are concerned. The switch unit, parts whereof are shown in Fig. 11, is then introduced into the box. The screw 10 bolts 46 passing through the brackets 44 and 45 serve to hold the stationary element or bar 80. When the rocker 83 is dropped into position to rest on the knife-edge 85 and the pad 121 to receive which the upturned edge 15 122 is provided, the switch unit is completely installed, the clip 90 being located in line with the clip 92, the latter of which may be regarded as a structural element of the frame 39, being permanently attached thereto, as are the binding posts 70, 71 and 123. The next step in the assemblage is to adjust the arm 31 upon the post 68, which is thereafter held in this position by a cotter pin 124. The plunger 78, if structurally separated 20 from the extension 74 of the switch arm, is placed in position with the collar 79 prior to setting the arm 31 on the post 68. The spring 77 thereafter holds said plunger in operative relation. The pencil brushes 72, 25 as in the conventional construction, are placed in operative position as a complete act of the installation, and not as an act of assemblage. To insert a pencil brush 72, it requires only that the spring 77 shall be 30 lifted to permit the introduction of the pencil into the head 73 under the spring 77. The spring 37 is now mounted to swing the pencil-provided end of the arm 31 over the dead button 102. If the installation calls 35 for a shunt-circuit, the jumper 104 is placed under the washers 67 connected with the button 103 and the adjacent button 66. The connector 125 is now united with the binding post 123, which completes the assemblage. 40 The operating current is completed within the box by the cover 40, and by the jumpers 91 and 115. Said jumpers are held in contact with the clips 90 and 92 and with the terminals 110 and 114, respectively, only 45 when in closed position on the box, in which position they are held by the latch 101.

When using the preferred form of the construction, the operation is as follows: Power being exerted through the transmission connector 36, the arm 31 is rocked on the post 68 to move the pencil 72 from the button 102 toward the opposite end of the series of buttons. The plunger 79 is carried over the rocker 83 in unison with the 50 movement of the pencil. The adjustment is such that the pencil brush 72 is electrically established in contact with the button 103 prior to the tipping of the rocker 83 which moves the head 82 thereof to engage the 55 head 81 on the bar 80. Thus the operative

current is established, first through the shunt winding of the motor, if such be employed, and subsequently through the motor and other diminishing resistance in the coil 48. It will also be noted that when the spring 37 60 is permitted to retract the arm 31, the plunger 78 tilts the rocker 83 to separate the heads 81 and 82 prior to the pencil 72 leaving the button 103. Hence, when the pencil 72 does leave the button 103, no arcing ensues at this point. The arcing due to the 65 break of the current is formed between the heads 81 and 82, and may in service destroy or otherwise impair these heads. It is for this reason that the head 82 is secured to 70 the bar 80 by a screw 126, and is held rigidly on said bar by side flanges 127, with which said head is provided. It will be seen that when the need arises to replace the head 81, this may be accomplished without removing 75 the bar 80, by releasing the screw 126 to lift the head 81 from the bar 80 to make room for a new head. If the head 82 is impaired, the rocker 83 is lifted from the knife-edge 85 and replaced by a new rocker. 80

It will be noted that the starting box above described, and as shown in the accompanying drawings, makes for simplicity of construction, ease and convenience of assemblage, and facility of repair and alteration. 85

Claims:

1. An apparatus as characterized, having a box-like body; a plurality of electric main terminals; a resistance coil mounted in said body, said coil having a plurality of section terminals; a plurality of terminal buttons, each electrically connected with one of said section terminals; a switch movable over said buttons, said switch having a circuit terminal; and a cover for said body, adapted to connect the terminal of said switch and the other of said main terminals. 100

2. An apparatus as characterized, having a box-like body; a plurality of main circuit terminals mounted on said body; a rheostat embodying coil section terminals, electrically connected with one of said circuit terminals; a switch movable over said section terminals; means for electrically connecting said switch and the other of said terminals; and a cover for said body for actuating said means to so connect said switch and terminal when said cover is actively disposed. 110

3. An apparatus as characterized, having a box-like body; a plurality of electric main terminals; a rheostat electrically connected with one of said terminals; a switch for said rheostat; a cover for said body; and means fixedly connected with said cover for electrically connecting said switch and the other of said terminals when said cover is closed on said body. 120

4. An apparatus as characterized, having a box-like body; a plurality of electric main terminals; a rheostat electrically connected 125

with one of said terminals, a switch controlling said rheostat; a cover for said body; means fixedly connected with said cover for electrically connecting said switch and the 5 other of said terminals when said cover is closed on said body; and means for holding said cover in closed position.

In testimony whereof I have signed my name to this specification in the presence of two subscribing witnesses.

MAX TAIGMAN.
